UNITED STATES PATENT OFFICE.

CLARA B. CURTISS, OF SAN FRANCISCO, CALIFORNIA.

HAND-RUBBER.

Specification of Letters Patent. Patented Apr. 9, 1918.

1,262,024.

Application filed March 1, 1917. Serial No. 151,774.

To all whom it may concern:

Be it known that I, Mrs. CLARA B. CURTISS, a citizen of the United States, residing at San Francisco in the county of San Francisco and State of California, have invented 5 certain new and useful Improvements in Hand-Rubbers; and I do hereby declare the following to be a full, clear, and exact 10 description of the invention, such as will enable others skilled in the art to which it app- 15 pertains to make and use the same.

This invention relates to a hand rubber and has for one of its objects the provision 15 of a device of this character, especially adapted to be used when washing clothing and the like, whereby the clothes may be 20 readily cleaned without rubbing them upon a washboard or similar device.

Another object of this invention is to 25 provide a frame having transverse and relatively spaced bars, adapted to move upwardly and downwardly upon the clothes or the like in the washtub for removing dirt and other foreign matter therefrom.

25 A further object of this invention is to provide handles disposed inwardly on the frame, whereby the device may be used in boiling water without danger of hurting the user's hands by engaging the sides of the 30 tub.

A still further object of this invention is 35 the provision of a hand rubber of the above stated character, which shall be simple, durable and efficient and which may be manufactured and sold at a comparatively low cost.

With these and other objects in view as will become more apparent as the description proceeds, the invention consists of certain 40 novel features of construction, combination and arrangement of parts as will be hereinafter more fully described and claimed.

For a complete understanding of my invention, reference is to be had to the following description and accompanying drawings, in which:

Figure 1 is a perspective view of a hand rubber constructed in accordance with my invention.

50 Fig. 2 is a longitudinal sectional view of the same.

Referring in detail to the drawing, the

numeral 1 indicates a pair of side members, which are connected adjacent their lower ends by transversely extending and relatively spaced bars 2. An intermediate member 3 is carried by the bars 2 in spaced relation to the members 1. The upper portions of the ends of the member 3 are cut away 60 for receiving handles 4, which are secured in any suitable manner to the inner faces of the members 1. The cut away portions of the ends of the member 3 present shoulders 5 on which the lower ends of the handles 4 rest and the cut away portion disposes the handles inwardly of the ends of the members 1, as clearly illustrated in Fig. 2. The handles 4 are provided with the usual finger openings 6, whereby the user may insert the fingers through the openings 6 to grip the handles.

In operation, the clothes and other articles to be washed are placed as customary in a washtub filled with soapy water and by 75 gripping each of the handles 4 and moving the device upwardly and downwardly within the washtub, upon the clothing and other articles, dirt and other foreign matter will be removed from the clothing or the like 80 articles. The handles 4 being disposed inwardly prevent the user's hand from coming in contact with the wall of the washtub, thus preventing the danger of the user's hand becoming hurt and also the handles on the 85 device project sufficiently far enough above the upper edges of the members 1 to permit the device to be used in boiling water without the user's hand coming in contact with the water.

While I have shown and described the preferred embodiment of my invention, it will be understood that minor changes in construction, combination and arrangement of parts may be made without departing from 95 the spirit and scope of the invention as claimed.

What is claimed is:

A hand rubber comprising a pair of relatively spaced members, an intermediate member, transversely extending and relatively spaced bars extending through the members adjacent their lower edges, said intermediate member having the upper portion of its ends cut away to form a pair of shoulders, handles supported upon the shoulders,

means for securing the handles to the inner faces of the first named members, said handles having openings to permit a person to grip the handles and being disposed inwardly 5 of the ends of the relatively spaced members, preventing a person's hands from coming in contact with the walls of a washtub.

In testimony whereof I affix my signature in presence of two witnesses.

CLARA B. CURTISS.
